Primary Examiner — Jennifer Rivard**CLAIM**

I claim the ornamental design for a safety razor handle, as shown and described.

DESCRIPTION

FIG. 1 is a left side view of a safety razor handle showing my new design;

FIG. 2 is a right side view of the safety razor handle;

FIG. 3 is a front view of the safety razor handle;

FIG. 4 is a rear view of the safety razor handle;

FIG. 5 is an enlarged top plan view of the safety razor handle; and,

FIG. 6 is an enlarged bottom plan view of the safety razor handle.

The ornamental design of a safety razor handle is shown in FIGS. 1 through 6 in the drawing sheet.

The safety razor handle is characterized by its surface pattern and overall shape.
